2,029,316

SYSTEM OF AMPLIFICATION OF ALTERNATING CURRENT

Louis A. Gebhard, Washington, D. C.

Application July 21, 1931, Serial No. 552,247

7 Claims. (Cl. 250—17)

(Granted under the act of March 3, 1883, as
amended April 30, 1928; 370 O. G. 757)

My invention relates broadly to a circuit arrangement for a multi-stage electron tube transmission system and more particularly to an arrangement of coupling circuit for the several stages of an electron tube transmitter for insuring the maximum transfer of energy from an oscillator circuit through a power amplification system to the transmission circuit.

This application is a continuation in part of 10 the subject matter disclosed in application Serial No. 60,071 which I filed jointly with John M. Miller on October 2, 1925 for System for the amplification of alternating currents.

A copending application Serial No. 551,783, 15 which I filed jointly with John M. Miller on July 18, 1931, which has become Patent No. 1,955,341, is also a continuation in part of the subject matter of the parent application Serial No. 60,071; the latter having, in due course, become 20 abandoned. Patent No. 1,955,341 deals more particularly with means for obtaining very high amplification ratios in successive stages of a high power transmitting system, whereas the instant case is directed to other objects such as the following:

One of the objects of my invention is to provide a simplified construction of multi-stage electron tube transmission system in which a maximum amount of energy may be transferred 30 through the several electron tube amplification stages to the transmission circuit.

Another object of my invention is to provide a circuit arrangement for a multi-stage electron tube transmission system wherein single inductance members provide the means for effecting the transfer of energy from one electron tube stage to a succeeding electron tube stage with tap connections extending to the single inductance units for balancing the operation of the 40 amplifier system.

Still another object of my invention is to provide a circuit arrangement for the electron tube stages of a high power transmitter system in which a single coupling inductance is disposed 45 between the output circuit of one electron tube stage and the input circuit of a succeeding electron tube stage with tap connections on the inductance leading to a tuned element for establishing a tuned path through the inductance 50 with additional taps interconnecting the output circuit of one tube with the input circuit of the succeeding tube and providing a path for balancing the capacity coupling of the tube electrodes in the tubes constituting the several electron tube 55 stages.

A further object of my invention is to provide an arrangement for coupling the electron tube circuits of a transmission system in which a single coupling inductance is so disposed intermediate the electron tube stages that separate 5 paths are provided through taps on the inductance for interconnecting the output of one electron tube with the input of a succeeding electron tube and establishing a tuned output circuit for the first tube while balancing the operation 10 of the electron tube stages through another path connected with the inductance.

A still further object of my invention is to provide a simplified construction of coupling circuit for the stages of a high power electron 15 tube transmission system in which a single inductance constitutes part of the output circuit of one electron tube and the input circuit of a succeeding electron tube with tap connections 20 thereon for balancing the circuits of the electron tube stages for insuring the maximum transfer of energy from one electron tube system to the succeeding electron tube system.

Another object of my invention is to provide a conductive coupling arrangement between a 25 crystal controlled electron tube oscillator and a power amplifier by which maximum power may be drawn from the crystal controlled oscillator circuit and transferred to a power amplifier system having means connected with the coupling 30 inductance for balancing the operation of the amplifier system.

Other and further objects of my invention will be understood from the specification hereinafter following by reference to the accompanying 35 drawing which diagrammatically illustrates a crystal controlled electron tube transmitter embodying the principles of my invention.

Referring to the drawing, the electron tube 1 is a low power tube and generates oscillations, 40 the frequency of which is controlled by the quartz crystal 4. The crystal is shown connected between the filament and grid of the electron tube. The battery 6 supplies a negative voltage to the grid of the electron tube through the choke coil 5. The condenser 53 is a radio frequency by-pass condenser. The filament 1a of the electron tube 1 is heated in a well-known manner with alternating current from the secondary 7 of a transformer having a primary 45 winding 19 connected to leads 11 over which the alternating current is supplied. The source of continuous voltage B₂ supplies the plate circuits of both the tubes 1 and 2 through leads 26, a reduced voltage being supplied to tube 1 through 50 55

the voltage divider consisting of resistances 21 and 28. The plate current of tube #1 is read on the ammeter I_{11} , the plate voltage by the voltmeter E_4 . The condenser 21 is a high frequency by-pass condenser. The high frequency output current is generated in the circuit comprising the parallel coil 18 and condenser 20 and is read by the ammeter I_{10} . The connections from the condenser 20 are formed by means of taps 20a and 20b on inductance 18. The return path for the output circuit of tube 1 to the source of plate potential is connected through inductance 18 through tap 70 as shown. It will be observed that the inductance provides extremely close coupling between the portions 18 and 19 of the inductance as will be hereinafter described more in detail. The portion of the inductance shown at 19 is arranged in such relation to the portion of the inductance shown at 18 that balanced operation of the circuits may be obtained as explained hereinafter.

Reference character 2 designates an electron tube of much higher power rating than tube 1. The exciting voltage is supplied to the grid of tube 2 through the connection 18a between coil 18 and the grid which includes the condenser 21 and ammeter I_5 . The grid is rendered negative by the voltage derived from the battery B_3 , through the connections 62, running from the junction of resistances 39 and 40 through the signaling key 35, the ammeter I_6 and choke coil L_8 to the grid 2b. When the signaling key 35 is open, the grid connection is made through resistance 38 to the extreme negative terminal of the source B_3 which effectively blocks the tube so that it no longer acts as an amplifier. The negative voltage applied to the grid of the tube 2 is sufficient in actual operation, that when signaling key 35 is closed and the exciting voltage is applied, only a small grid current is registered by the ammeter I_5 and only a slight reduction in the current indicated by ammeter I_{10} is noted. The filament 2a is supplied from the secondary 12 of a transformer having primary winding 16 connecting to supply line 17. The plate supply voltage for the tube 2 is furnished by the source B_2 through the leads 26, ammeter I_8 and choke coil 32. The condenser 22 serves as a blocking condenser for the continuous plate voltage and as a by-pass for high frequency currents.

The amplified output current of high frequency flows in the circuit comprising the coil 24, condenser 25 and ammeter I_4 , which circuit is connected through taps 25a and 25b with the turns of inductance shown at 24. The return plate circuit path for tube 2 extends through tap 71 to the balancing portion of the inductance indicated at 72.

My invention provides for a connection containing the variable condenser 23 and turns 19 of coil 18 in combination with the other features described. With a suitable number of turns 19 in coil 18 and proper polarity of the tapped connection 19a on this coil and a suitable value of capacity in variable condenser 23, reaction is prevented between the output circuit and input circuit of the electron tube 2 through the effective capacity between the plate and grid electrodes of the tube, and other extraneous capacities such as leads, terminals and apparatus associated with the circuits. The arrangement of coil 24 with its balancing turns 72 and its associated taps is similar to the arrangement described in connection with coil 18. The turns of

inductance designated at 19 are closely coupled with the turns of inductance designated at 18. The tap from the portion of inductance 18 which is taken at point 18a on inductance 18 serves to excite the grid of electron tube 2. The tap 19a taken from the turns 19, serves to establish a path through which a voltage opposing the voltage in the turns 18 of the inductance is set up for balancing the operation of the tube system through a single coupling inductance. That is to say, the current feed back through the inter-element capacity of tube 2 across electrodes 2b and 2c through condenser 21 and tap 18a causes a voltage to be set up across turns 18 which is 180° out of phase with the voltage set up in the turns of inductance 18 due to the current through the path containing condenser 23, tap 19a and turns 19. The regulation of the balancing path is determined by moving adjustable contactor 19a or changing the effective value of variable condenser 23.

The tube 2 functions as an amplifier for increasing the amplitude of the radio frequency energy developed by the oscillator 1 impressing the energy thus developed upon the electron tube 3. The exciting voltage for the grid of electron tube 3 is supplied through the tapped connection 24a on coil 24 which contains the ammeter I_3 . The rated power of tube 3 can be much larger than that of tube 2, but normally the ratio in this case would be less than the ratio of the rated powers of tube 2 to tube 1. For example, if tube 3 is a 20-kilowatt tube, that is a tube capable of supplying 20 kilowatts of power to the transmitting antenna, under normal conditions of operation, tube 2 might be a one kilowatt tube and tube 1 a five or ten watt tube. Since tube 3 is the last tube it is advantageous to excite this tube normally, thus a relatively large amount of power is taken from the exciting tube 2. Reactions between the output circuit of tube 3 and the input circuit are prevented by the connection running from the tap 63 on coil 24 and including variable condenser 52 in a similar manner to that explained before for tube 2. The supply of voltage for the plate of tube 3 is furnished by the source B_4 , through leads 61, and choke coil 49. 51, 42 and 50 are the customary by-pass condensers. The output circuit of tube 3 includes the coupling coil 54 which is coupled to coil 55 in 50 the antenna system 57 and counterpoise 58. The antenna circuit is tuned by varying the position of the tap 55a on coil 55 and the variable condenser 56. Filament electrode 3a is heated from a filament transformer comprising primary winding 46 and secondary winding 43 supplied by power through leads 47. A common bus connection 60 is provided for all of the tube circuits as shown. The keying circuit may be distantly controlled through winding 36 which is connected 60 to line wire system 37.

It will be observed that the taps 20b and 25b on inductances 18 and 24 respectively, are beyond the return path taps 70 and 71 on the respective inductances for increasing the balancing effect 65 in each of the coupling systems.

I utilize a single coupling inductance disposed between the output circuit of one electron tube and the input circuit of the succeeding electron tube and utilizing the taps along the inductance 70 units in such arrangement that the single coil functions in a multiplicity of different ways. When coupling the output of an oscillator to the input of the power amplifier, the coupling inductance provides an oscillatory path for the 75

oscillator at the same time effecting a transfer of energy to the power amplifier and in addition effecting a balance for the operation of the electron tube circuits.

5 In the case of the interconnection of the output circuit of one stage of power amplification with a succeeding stage of power amplification, the single inductance provides a tuned path for the output circuit of one power amplifier stage 10 while effecting a transfer of energy to the input circuit of the succeeding power amplifier stage and also providing a balancing circuit for insuring the balanced operation of the several amplifier stages. This arrangement provides for the 15 simplified assembly of an electron tube transmitter as the mechanical means for mounting the coupling inductance may be of simplified form. Better insulation may be obtained by virtue of the simplified mounting of the inductance. 20 Greater efficiency in operation is obtained by increase in the transfer of energy from the oscillator to the transmission circuit.

In order to eliminate the undesirable effects of the alternating current which is utilized for 25 heating the cathodes 1a, 2a and 3a, a center tap is provided on the secondary windings 43, 12 and 7 of the filament heating transformers. In order to afford a low reactance path for the radio frequency return currents to the cathodes, condensers 8, 9, 14, 15, 44 and 45 are connected across 30 each half of the secondary windings 7, 12 and 43 respectively, of the filament heating transformers. Resistances are provided in each of the voltmeter circuits. Meter E₄ has a resistance 30 35 disposed in series therewith, while meters E₁, E₂ and E₃ have resistances 48, 41 and 28 disposed in circuit therewith. A resonance circuit including inductance 59 and ammeter I₂ is disposed between the output of tube 3 and the coupling system which connect with the antenna.

40 Tap 70 is connected to ground through by-pass condenser 31. Similarly tap 71 is connected to ground through by-pass condenser 42. These connections serve to hold the potentials of the points on the inductances to which they are connected at substantially radio frequency ground potential.

45 By-pass condensers 8 and 9 on the filament connections of tube 1 serve to hold the filament at substantially radio frequency ground potential. Similarly condensers 14 and 15 connected to the filament operate to hold the filament of tube 2 at substantially radio frequency ground potential. Condensers 44 and 45 serve a similar 50 function with respect to the filament of tube 3.

55 The tap 18a should be located on the same side of tap 70 as tap 20a is located. Tap 19a should be located on the other side of tap 70. This arrangement is necessary to insure the 180° phase 60 displacement. Tap 20a may embrace the total coil and does not necessarily have to be placed at any particular arrangement with respect to tap 18a. Tap 20b may be placed as shown in the diagram or coincident with tap 70. If it is placed 65 coincident with tap 70 then it is essential that turns 19 be coupled very closely to the turns 18 in order to obtain a satisfactory balance. This can be done by designing the coils to have a large diameter and a short length. Coils of extremely great length and small diameter have 70 been found to be unsatisfactory. If, however, tap 20b is arranged to be coincident with tap 19a, then coupling between turns 19 and turns 18 is secured in an additional manner from that previously described, namely, through the resonant 75

circuit comprising condenser 20, turns 18 and turns 19. It is possible by this arrangement then to use slender coils with fairly great length.

In operation balance may be considered from two standpoints:

(a) From the standpoint that energy entering the system is not transmitted through the system and lost but is retained in the system and made to do work in the input circuit of the tube.

(b) From the standpoint that energy in the output circuit of the tube is prevented from entering the input circuit of that same tube and causing difficulties due to self-oscillation in that tube.

Considering the system from the first standpoint, the excitation voltage is obtained from the resonant circuit comprising coil 18 and condenser 20, from condenser 21 to the grid circuit of tube 2 comprising grid 2b and filament 2a. The resonant circuit comprising condenser 25 and coil 24 is therefore subject to this voltage and after this circuit is tuned to resonance will consume considerable power to such an extent that oscillations of the crystal circuit will be stopped. However with the addition of the balance, a voltage 180° out of phase with that due to the excitation voltage is impressed between the anode 2c and filament 2a through tap 19a and condenser 23. With proper adjustment of this tap and condenser it is possible to substantially utilize voltage between these terminals due to excitation and thus the reaction upon the crystal circuit of resonant circuit comprising condenser 25 and coil 24 is substantially eliminated, the energy in the crystal circuit being compelled and confined to the input circuit of tube 2.

With respect to tube 3 and its resonant input and output circuits the same method of operation is secured.

With respect to the second purpose, mainly to prevent self-oscillation in the system or regeneration injurious to the crystal in the master circuit, the system may be considered as having a voltage existing between the anode 2c and the filament 2a of tube 2. This voltage is the voltage existing in the output circuit of tube 2 which causes a current to be set up at two different paths. One of these paths is through the inter-element capacity of tube 2 between its anode 2c and its grid 2b through condenser 21 and tap 18a through tap 70 to ground. A second circuit comprises condenser 23, tap 19a and tap 70 to ground. The current through the first circuit causes a potential to be set up between tap 18a and tap 70 which is substantially across the input circuit of tube 2. The current through the second circuit causes a magnetic field due to passing through turns 19 which field reduces the voltage in turns 18 substantially 180° out of phase with the voltage due to the current in the first circuit. If the magnitudes of these voltages are properly adjusted the resultant voltage is zero. This may also be considered from the standpoint of coupling, in which case with this proper adjustment the coupling between the output circuit and the input circuit of the tube will be substantially zero. Thus regeneration in the tube such as might cause injury to crystal 4 or self-oscillation of the amplifier circuit is avoided.

I have found the operation of the transmission system of my invention highly practical and while I have described my invention in one of its preferred embodiments, I desire that it be understood that modifications may be made and

that no limitations upon my invention are intended other than are imposed by the scope of the appended claims.

The invention herein described, may be manufactured and used by and for the Government of the United States of America, for governmental purposes, without the payment of any royalties thereon.

What I claim as new and desire to secure by Letters Patent of the United States is as follows:

1. A radio transmitter circuit including a piezo electric crystal controlled oscillator having an input circuit and an output circuit, a power amplifier the input circuit of which is adapted to receive energy transferred from said oscillator, means including a single inductance winding in said oscillator output circuit for coupling the same with said amplifier input circuit and for transferring energy to said amplifier, and means including a keying-circuit relay for changing the grid bias applied to said amplifier and for causing said amplifier to transmit code signals.

2. A radio transmitter circuit including an oscillator having an input circuit and an output circuit, a power amplifier the input circuit of which is adapted to receive energy transferred from said oscillator, means including a single inductance winding in said oscillator output circuit for coupling the same with said amplifier input circuit and for transferring energy to said amplifier, and means including a keying-circuit relay for changing the grid bias applied to said amplifier and for causing said amplifier to transmit code signals.

3. In a radio transmission system, a multiplicity of electron tube stages each having input and output circuits, and means interconnecting the output circuit of one electron tube stage with the input circuit of a succeeding electron tube stage comprising a single inductance having tapped connections leading to the last mentioned circuits, a tuning element connected in shunt with a portion of said inductance, a balancing circuit connected in series with another portion of said inductance, and means including a keying-circuit relay for changing the grid bias applied to one of said tube stages and for causing said system to transmit code signals.

4. In a radio transmission system, a keying-circuit relay, a multiplicity of electron tube stages each having input and output circuits, means for causing said keying-circuit relay to effect a change of bias potential applied to one of said input circuits, and means interconnecting the output circuit of one electron tube stage with the input circuit of a succeeding electron tube stage comprising a single inductance, said inductance having a point therein connected to ground with the turns on one side of said grounded point connected in the output circuit of one electron tube and adjustably included in the input circuit of the succeeding electron tube and the turns of said inductance on the other side of said grounded point being connected for balancing the operation of said electron tubes.

5. In a radio transmission system, a multiplicity of electron tube stages each having input

and output circuits and means interconnecting the output circuit of one electron tube stage with the input circuit of a succeeding electron tube stage comprising a single inductance, said inductance having a point therein connected to ground, a tuning condenser, said tuning condenser having connections terminating in taps, one of said taps being disposed adjacent said grounded point and the other of said taps being removed from said grounded point, a tap on said inductance extending to the output circuit of one electron tube, a tap on said inductance intermediate the taps leading to said tuning condenser for applying excitation potential to the input circuit of the succeeding electron tube, and a balancing circuit tap connected to said inductance at a point beyond the limits of the tap connecting to one side of said tuning condenser, and means including a keying-circuit relay for changing the grid bias applied to one of said tube stages and for causing said system to transmit code signals.

6. In a radio transmission system, a multiplicity of electron tube stages each having input and output circuits, and means interconnecting the output circuit of one electron tube stage with the input circuit of a succeeding electron tube stage comprising a single inductance, a connection to ground to a point on said inductance, an adjustable tap adjacent one end of said inductance connected to the output circuit of one electron tube, a tuning element, adjustable taps connecting said tuning element to points along said inductance displaced from said first mentioned tap, an excitation tap adjustably connected to said inductance intermediate the terminals of said tuning element and connected with the input circuit of the succeeding electron tube, a balancing tap connected to said inductance, beyond the grounded point thereof and beyond the connection of said tuning element with said inductance for establishing opposing current paths through said inductance for balancing the operation of said electron tube stages, and means including a keying-circuit relay for changing the grid bias applied to one of said tube stages and for causing said system to transmit code signals.

7. In a radio transmission system, a multiplicity of electron tube stages each having input and output circuits and means interconnecting the output circuit of one electron tube stage with the input circuit of a succeeding electron tube stage comprising a single inductance having tapped connections leading to the last mentioned circuits, a tuning condenser connected in shunt with a portion of said inductance, a balancing circuit extending from one of the circuits of the succeeding electron tube to a tap on said inductance, said tap being located beyond the connection of one side of said tuning condenser with said inductance, said balancing circuit extending through said inductance to a point intermediate the connections of said tuning condenser with said inductance for establishing paths for opposing currents through said inductance.

LOUIS A. GEBHARD.
